UNITED STATES PATENT OFFICE

FREDERICK WILLIAM MULLER, OF ATLANTA, GEORGIA

TYPE-FORM STORAGE AND LOCK-UP FRAME

Application filed February 12, 1929. Serial No. 339,410.

This invention relates to an improved printer's appliance, which because of the function which it serves may be conveniently and briefly titled a type form storage and lock up frame and it has more particular reference to a structure for use in printing establishments, newspaper offices, linotype rooms and kindred business places.

In accordance with my construction the invention comprises a simple multiple part frame, wherein the parts are separably connected together and cooperate in a manner to produce a structure which is efficient in performance, positive and dependable in action, economical and otherwise proficient in fulfilling the requirements of an invention of this class.

The invention is regarded as original in the trade, in that it does away with string tying of forms, a custom in vogue since time immemorial. It avoids the practice of six or more typings and un typings to make corrections when proofing the work. As a rule, approximately thirty minutes are spent in doing this particular work, and this is overcome with the present sectional frame wherein assembly is permitted in less than five minutes, the correction made and the form readjusted in minimum time, saving on an average of twenty minutes on each form handled. I further have evolved and produced a structure which can be successfully locked in a chase, when taken from storage, and this without delay.

The structure is unusually practical, being made to accommodate regular type measurement. It can always be locked up at right angles and it can be taken to the proofing press and impressions taken of types set therein in a convenient manner.

Other features and advantages will become more readily apparent from the following description and drawings.

In the drawings:

Figure 1 is a top plan view of a form or frame constructed in accordance with the present invention.

Figure 2 is a transverse section through the same.

Figure 3 is a perspective view of one cor-

ner portion showing the novel quick detachable retaining means.

In carrying out the invention, I provide a substantially rectangular frame composed of four distinct parts namely a pair of spaced parallel side members 4 and a pair of duplicate end members 5. These members are constructed of appropriate material, and when made of metal, the side members are longitudinally bored for sake of lightness in weight. The opposite ends of the members 4 and 5 are of the construction detailed in Figure 3. Referring to this figure, it will be seen that each side member is bifurcated at each end and the furcations are designated by the reference characters 6 and 7 respectively, the outer furcations 6 being slightly longer than the inner ones.

Extending crosswise of these furcations and approximately half as high as the furcations are comparatively short cross pieces or plates 8 and 9 adapted to function as keepers.

The complementary end of the end member 5 is directed at right angles as at 10 and adapted for reception between the furcations 6 and 7 to form interlocking joints. The lower edge of this end portion 10 is formed with spaced notches 11 to engage the keeper plate and thereby provide a dependable and firm joint.

The frame will be made in practical sizes for printing office and newspaper ad work. The type pieces 4 may range from thirty-six, fifty-four and seventy-two picas more or less, whereas the end members may range from twenty-four, thirty-six, and sixty picas more or less. Also provide a structure, one or more columns in width when used by newspapers. In fact, it is within the conception of the invention to make the frame for regular type measurement.

In operation, the types are assembled in the frame in the customary manner. When this has been finished, the complete assembly is pulled in on the galley. It is then taken to the proofing press, inked and the impression taken.

In composing, it will only be necessary to lift the end member and to adjust it out one notch to make a correction and to replace the end member and to force it down so that it will

be flush with the complemental side members. This locks the form. It can then be placed in chase ready to be locked up for the press and the other type matter, and cuts can be locked in the same form if necessary. In removing 5 from chase, the operator moves the frame on the form and slips it on a board and files it away for future reference, labelling it before putting it on the shelf.

A careful study of the detailed description 10 in conjunction with the drawing will enable the reader to obtain a clear understanding of the features, construction and method of use. Therefore a more lengthly description is regarded as unnecessary.

15 Minor changes in the shape, size, materials, and rearrangement coming within the field of invention claimed may be resorted to, in actual practice, if desired.

I claim:

20 In a type form storage and lock up frame of the class described, a pair of longitudinally spaced parallel side members, having their opposite ends bifurcated longitudinally, transverse keeper plates embedded in said furcations and bridging the space between the furcations, and a pair of duplicate end members having laterally directed end portions removably receivable between the furcations, 25 said end portions having spaced notches forming keeper seats for removable reception of said keepers.

In testimony whereof I affix my signature.
FREDERICK WILLIAM MULLER.
